(57) CLAIM

The ornamental design for a box for confectionary articles, as shown and described.

DESCRIPTION

FIG. 1 is a perspective view of a box for confectionary articles in accordance with my new design;

FIG. 2 is a top plan view of the box of FIG. 1;

FIG. 3 is a bottom view thereof;

FIG. 4 is a side elevational view of the right-hand side of the box of FIG. 1;

FIG. 5 is an elevational view of the side of the box opposite FIG. 4.

FIG. 6 is a front elevational view thereof; and,

FIG. 7 is a rear elevational view thereof.

The surface areas on the various drawing views having stippled shading of contrasting densities indicate areas of contrasting color on the confectionary box and form part of the claimed design. The contents of the box shown in broken lines in FIGS. 1 and 2 form no part of the claimed design.
